UNITED STATES PATENT OFFICE.

ANDREW W. GRAHAM, OF BUFFALO, NEW YORK.

LIQUID-RECEPTACLE ATTACHMENT.

1,366,789.

Specification of Letters Patent. Patented Jan. 25, 1921.

Application filed December 10, 1919. Serial No. 343,912.

To all whom it may concern:

Be it known that I, ANDREW W. GRAHAM, a citizen of the United States, residing at Buffalo, in the county of Erie and 5 State of New York, have invented certain new and useful Improvements in Liquid-Receptacle Attachments, of which the following is a specification.

This invention relates to liquid receptacle attachments used for closing such receptacles and affording means for attaching a flexible tube such as is used in syringes and the like.

One important object of the invention is 15 to provide a novel form of cover, cap or stopple for bottles, jars and other containers or receptacles arranged in such a manner as to make it possible to convert any ordinary glass jar or household bottle into 20 a hygienic and sanitary liquid container for use as a syringe, douche, feeding bottle or the like.

A second important object of the invention is to provide a combination cover or 25 closure for the purpose having a novel construction whereby it can be readily attached to an ordinary container by a screw collar, wire lever clamp, by friction or by any other desired means.

30 A third important object of the invention is to provide a cover, cap or stopper adapted to be applied to any ordinary container and having an outlet for fluid and an inlet for air.

35 A fourth important object of the invention is to provide a combination container cover having means for supplying air to the container to prevent the formation of a vacuum as would be caused by withdrawing 40 the contents through a suitable opening or a hose connected to said cover.

A fifth object of the invention is to provide an improved stopple constructed to convert any ordinary bottle or jar into a 45 hygienic device to permit feeding of a patient through the rectum, for feeding stock or the like.

With the above and other objects in view, as will be hereinafter apparent, the invention 50 consists in general of certain novel details of construction and combination of parts hereinafter fully described, illustrated in the accompanying drawings and specifically claimed.

55 In the accompanying drawings like char-

acters of reference indicate like parts in the several views, and:

Figure 1 is a side elevation, showing the complete apparatus.

Fig. 2 is a sectional view, showing the improved stopple applied to a small mouthed bottle.

Fig. 3 is a similar view, showing the application of the device to a medium bottle.

Fig. 4 is a similar view with the stopple applied to a wide mouthed jar and held thereon by a screw ring.

Fig. 5 is a section showing a modification arranged for application to one size only of bottle.

In carrying out this invention it is intended to use the attachment in connection with any ordinary bottle or jar such as indicated in Fig. 1 at 10, the bottle being provided with some means of holding it at an elevation such as typified by the band or clamp 11 and the hook 12. In this view the attachment forming the invention is shown at 13, the attachment being held in place on the receptacle by the wire clamp 14 and 70 being provided with a tube or hose 15.

The invention proper consists of a body or base 16 having extending therefrom a series of receptacle engaging projections 17, 18 and 19 here shown as concentric, 85 although it will be obvious that the arrangement may be varied. Moreover, each of these projections is here shown as stamped, with a portion of the base, from a single piece of sheet metal, the outer projection 90 or annulus having its edge beaded over, as at 16', so that all are held together firmly without soldering or riveting. However, other forms of construction may be used; as, for instance, the device may be 95 die cast or may be molded from rubber, papier mâché, hard fiber, celluloid or other material. In the present instance the inner annuli are slotted, as at 20, to form yieldable supports for compressible covers or 100 rings of cork, rubber or the like, as at 21.

Within the area circumscribed by the inner annulus or projection 17 is an outlet opening 22 extending through a tubular projection 23, forming means for attaching 105 a rubber hose, pipe or tube. Also, similarly situated, is an inwardly projecting tube 24 carrying an inwardly opening check valve 25, the valve in Fig. 2 being a slitted rubber bulb, while that in Fig. 3 is a ball 110

valve and that in Fig. 4 is a flattened rubber tube.

In Fig. 5 is disclosed a modification in which only the inner annulus is used, the modification being adapted for narrow necked bottles only.

In Figs. 2 and 3 the device is connected to the receptacle frictionally in the usual manner of a stopper, while in Fig. 4 the device is held on a wide mouthed jar by a screw threaded ring 26.

In using the invention any ordinary bottle or jar is filled with the liquid to be used and the closure applied thereto. The device may then be inverted, whereupon the contents of the receptacle will pass out of the opening 22, while air will flow in through the inlet.

When using the device for the purpose of administering an enema or douche the receptacle may be held in one hand, while the tube is manipulated with the other so that one may see what he gets and get what he sees. Also the device may obviously be used for rectal feeding and for feeding stock, etc.

Attention is invited to the fact that, by using this closure or attachment, a surgically clean glass vessel can be used as the receptacle or container, thus preventing danger of infection.

There has thus been provided a simple and efficient device of the kind described and for the purpose specified.

It is obvious that many minor changes may be made in the form and construction of the invention without departing from the material principles thereof. It is not, therefore, desired to confine the invention to the exact form herein shown and described, but it is wished to include all such as properly come within the scope claimed.

Having thus described the invention, what is claimed as new is:

1. A stopple for the purpose described consisting of a base and a plurality of projections extending to substantially the same distance therefrom and adapted to form closures for receptacles having mouths of different sizes.

2. A stopple for the purpose described, including a base member, and a plurality of concentric annuli projecting to substantially the same distance therefrom to fit different sizes of receptacle mouths.

3. A stopple for the purpose described, including a base member, and a plurality of concentric annuli projecting to substantially the same distance therefrom to fit different sizes of receptacle mouths, certain of said annuli being provided with compressible coverings whereby to insure close contact with the receptacle mouths.

4. A stopple for the purpose described, including a base member, and a plurality of

concentric annuli projecting to substantially the same distance therefrom to fit different sizes of receptacle mouths, certain of said annuli being provided with compressible coverings whereby to insure close contact with the receptacle mouths, said coverings being exteriorly frusto conical in form.

5. A stopple for the purpose described, including a base member, and a plurality of concentric annuli projecting therefrom to fit different sizes of receptacle mouths, said base member having an inlet and an outlet passage within the area circumscribed by the innermost annulus, the inlet passage being provided with an inwardly opening check valve.

6. A stopple for the purpose described, including a base member, and a plurality of concentric annuli projecting therefrom to fit different sizes of receptacle mouths, certain of said annuli being provided with compressible coverings whereby to insure close contact with the receptacle mouths, said base member having an inlet and an outlet passage within the area circumscribed by the innermost annulus, the inlet passage being provided with an inwardly opening check valve.

7. A stopple for the purpose described, including a base member, and a plurality of concentric annuli projecting therefrom to fit different sizes of receptacle mouths, certain of said annuli being provided with compressible coverings whereby to insure close contact with the receptacle mouths, said coverings being interiorly frusto conical in form, said base member having an inlet and an outlet passage within the area circumscribed by the innermost annulus, the inlet passage being provided with an inwardly opening check valve.

8. A stopple for the purpose described, including a base member, and a plurality of concentric annuli projecting therefrom to fit different sizes of receptacle mouths, the outer annulus being of sufficient sizes to embrace the mouth of a jar, and a screw ring engageable with the stopple, and a jar mouth whereby to hold the stopple thereon.

9. A stopple for the purpose described, including a base member, and a plurality of concentric annuli projecting therefrom to fit different sizes of receptacle mouths, the outer annulus being of sufficient sizes to embrace the mouth of a jar, and a screw ring engageable with the stopple, and a jar mouth whereby to hold the stopple thereon, certain of said annuli being provided with compressible coverings whereby to insure close contact with the receptacle mouths.

10. A stopple for the purpose described, including a base member, and a plurality of concentric annuli projecting therefrom to fit different sizes of receptacle mouths, the outer annulus being of sufficient sizes to

embrace the mouth of a jar, and a screw ring engageable with the stopple, and a jar mouth whereby to hold the stopple thereon, certain of said annuli being provided with 5 compressible coverings whereby to insure close contact with the receptacle mouths, said base member having an inlet and an

outlet passage within the area circumscribed by the innermost annulus, the inlet passage being provided with an inwardly opening 10 check valve.

In testimony whereof I affix my signature.

ANDREW W. GRAHAM.
